UNITED STATES PATENT OFFICE.

LEWIS A. BROWN, OF ST. LOUIS, MISSOURI.

POST OR COLUMN.

No. 925,865.

Specification of Letters Patent.

Patented June 22, 1909.

Application filed March 25, 1909. Serial No. 485,836.

To all whom it may concern:

Be it known that I, LEWIS A. BROWN, a citizen of the United States, residing at St. Louis, Missouri, have invented a new and useful Improvement in Posts or Columns, of which the following is a specification.

This invention relates to reinforced posts and columns, the object being to provide a strong and durable concrete or cement post or column having a sheet metal reinforcement embedded therein, extending longitudinally, and being bent to provide a series of radial arms, said arms having integral projections, and being also provided with holes 15 into which the concrete enters, whereby the reinforcement becomes strongly united with the concrete.

Another object is to provide a reinforced post or column of maximum strength and durability, and of inexpensive construction, whereby the post or column is made available for ordinary and general use.

In the accompanying drawing, wherein I have shown one embodiment of my invention, Figure 1 is an elevation of a post constructed in accordance with the principles of my invention. Fig. 2 is a perspective view of the reinforcing member. Fig. 3 is a sectional view of a round post, taken on the line 3—3 of Fig. 1. Fig. 4 is a sectional view illustrating a preferred arrangement of the reinforcement in a polygonal post or column. Fig. 5 is a view of part of the sheet metal showing the slits therein. Fig. 6 is a sectional view of part of the sheet metal showing the lateral projections formed between the slits.

The metallic portion or reinforcement consists of a sheet metal plate comprising a central portion 1, bent in opposite directions, as shown at 2 and 3, whereby the portions 4 are caused to lie against the central portion. The edges or lateral portions 5 bend outwardly substantially at right angles to the central portion. Through laterally extending portions 5, and through the overlapping portions 1 and 4 crossed slits are cut, and the triangular portions formed between the slits are bent laterally, providing lateral extensions 6. These devices are formed in staggered relation on each wing or arm of the

sheet metal reinforcement as shown in Fig. 2. The reinforcement thus formed is then enclosed in the mold and the cement or concrete is poured into the mold, thus entirely embedding the reinforcing member, and entering the holes formed by the extensions 6. The projections 6, and the holes having the concrete therein, cause a strong union of the concrete and the reinforcement. At suitable intervals along the post grooves 7 are formed to receive the fastening devices whereby the wires, etc., are secured to the posts.

When a polygonal post is formed the wings or arms of the reinforcement project toward the corners, as shown in Fig. 4. Grooves 8, for like purpose as the grooves 7, are formed in the corners of posts of the polygonal form.

I am aware that there may be variations and modifications in the arrangement and construction without in the least departing from the spirit and scope of the invention. I do not restrict myself to identical forms or details, but

What I claim and desire to secure by Letters Patent is—

1. A post comprising a concrete body, and a sheet metal reinforcement comprising a central portion having lateral portions bent around and overlapped against said central portion and having its edges extending laterally at right angles to said central portion, substantially as specified.

2. In combination, a concrete post, a vertical sheet metal plate embedded in said concrete having two bends between its median line and each edge whereby that portion between each two bends is caused to lie against the central portion on opposite sides, and the portions between the two outer bends and the edges are extended laterally at right angles to the central portion, and a series of projections on said sheet metal plate.

In testimony whereof I have hereunto set my hand, in the presence of two witnesses, this 23 day of March, 1909.

LEWIS A. BROWN.
